US00D870577S

(12) **United States Design Patent** (10) **Patent No.:** **US D870,577 S**
(45) **Date of Patent:** **** Dec. 24, 2019**

(54) **PRESSURE MEASURING DEVICE WITH WIDE TOP AND BOTTOM SEGMENTS**

(71) Applicant: **KISTLER HOLDING AG**, Winterthur (CH)

(72) Inventors: **Daniel Fürer**, Zurich (CH); **Christof Sonderegger**, Frauenfeld (CH); **Daniel Buerki**, Effretikon (CH)

(73) Assignee: **Kistler Holding AG**, Winterthur (CH)

(**) Term: **15 Years**

(21) Appl. No.: **29/640,979**

(22) Filed: **Mar. 19, 2018**

Related U.S. Application Data

(62) Division of application No. 35/501,972, filed on Sep. 1, 2016 (U.S. filing date under 35 U.S.C. 384), and having an international filing date of Sep. 1, 2016, now Pat. No. Des. 817,795.

(51) **LOC (12) Cl.** **10-04**

(52) **U.S. Cl.** **D10/85**

(58) **Field of Classification Search**

USPC D10/83, 85; D23/233, 235

(57) **CLAIM**

The ornamental design for pressure measuring device with wide top and bottom segments, as shown and described.

DESCRIPTION

FIG. 1 is a front view.

FIG. 2 is a right side view.

FIG. 3 is a rear view.

FIG. 4 is a left side view.

FIG. 5 is a top perspective view taken from the front and left side.

FIG. 6 is a top perspective view taken from the left side and rear.

FIG. 7 is a front view.

FIG. 8 is a right side view.

FIG. 9 is a left side view.

FIG. 10 is a rear view.

FIG. 11 is a top perspective view taken from the left side and rear, and,

FIG. 12 is a top perspective view taken from the front and left side.
